UNITED STATES PATENT OFFICE.

HORACE Q. PLUMMER, OF MAPLEWOOD, INDIANA, ASSIGNOR, BY DIRECT AND MESNE ASSIGNMENTS, TO THE AMERICAN MANUFACTURING COMPANY AND HENRY T. HEARSEY, OF INDIANAPOLIS, INDIANA.

BICYCLE-BELL.

SPECIFICATION forming part of Letters Patent No. 632,427, dated September 5, 1899.

Application filed October 21, 1897. Serial No. 655,899. (No model.)

To all whom it may concern:

Be it known that I, HORACE Q. PLUMMER, a citizen of the United States, residing at Maplewood, in the county of Hendricks and 5 State of Indiana, have invented certain new and useful Improvements in Bicycle-Bells; and I do declare the following to be a full, clear, and exact description of the invention, such as will enable others skilled in the art 10 to which it appertains to make and use the same, reference being had to the accompanying drawings, and to the letters of reference marked thereon, which form a part of this specification.

15 My invention relates to that class of bells or gongs that are operated by means of moving parts of the bicycle; and it consists of a bell or gong, a supporting-frame adapted to be attached to a bicycle-pedal, a controlling-lever, and in the parts and combination thereof forming the operating mechanism, as will be more fully described hereinafter and particularly pointed out in the claims.

20 My object is to provide an alarm-bell for bicycles which shall automatically cause a continuous alarm, when desired, as long as the bicycle is in motion and which may be manipulated to cease without requiring the use of the hand, which may be otherwise engaged in emergencies. This is attained in 25 my invention, which is, furthermore, cheaply constructed, durable, and economical in use.

Referring to the drawings, Figure 1 represents a rear elevation of a right-side bicycle-pedal and portion of crank, showing my bell attached to the pedal; Fig. 2, a plan view of the uncovered frame, showing the trip mechanism set "out of gear," so the bell will not be sounded. Fig. 3 is a like view showing 30 the mechanism "in gear;" Fig. 4, a central sectional view of frame and bell, showing manner of attaching to the pedal; Figs. 5 and 6, trip-arms; Fig. 7, a side view of controlling-lever, and Fig. 8 a plan of securing-straps.

40 In the drawings, A designates the bell-frame; B, the bell; C, the pedal-frame; D, the pedal-axle; E, the crank; F, the trip-arm; G, the trip-lever; H, the controlling-lever; I, the auxiliary lever; L, the clapper-arm, 45 and M the clapper-spring.

In construction I make a frame A of suitable size and material, usually of circular form, having a flange *a* turned down to inclose the mechanism, and extending over the edges of the bell it prevents the latter from 55 becoming filled with dirt from the road or foot. The arm K is preferably made integral with the frame and has a boss T, having a screw-threaded hole, into which is fitted the threaded stud *b* of the bell, by which it is 60 supported on the frame. The frame has a bearing against the under side of frame of the pedal and is preferably secured by means of one or more straps, as R, passing over the barrel Q of the pedal and into the ends of 65 which are inserted threaded screws *t*, by which rigidity is secured.

At the underside of the frame the clapper-arm L is pivoted at *l* and the arm is connected by a suitable spring M, secured at *n* to the 70 frame. At a suitable point adjacent I pivot a trip-lever G centrally, as at *m*, the inner end of which lever is connected to the clapper-arm, while the opposite outer end protrudes beyond the frame somewhat. At the 75 rear or side toward the point at which the controlling-lever is situated is a notch O and an adjacent incline P, sloping away from the top of the notch.

The controlling-lever H is pivoted to the 80 frame at a suitable point, as at *h*, and has its inner end N rounded and adapted to engage the notch O. The auxiliary lever I is shorter than lever H and has its inner end pivoted also to the frame, as at *i*. A connecting-bar 85 J has one end pivoted to the lever H, as at *d*, and the opposite end is pivoted to the lever I, as at *e*, by which both levers are caused to move in unison. The outer end of each lever is turned upward, so as to extend above the 90 top of the pedal, and they are also slightly bent outward to adapt the upper ends to straddle the foot of the rider.

The trip-arm F has a hub having a bore *f*, adapted to fit over the end *u* of the axle D, 95 which when attached to the crank binds and secures the hub against the face of the boss at the end of the crank. Suitable dowels may be used, if desired. The hub may have one or more arms, as four, F'. The end of each 100

arm preferably has a raised semicircular face *c* to engage the end of the trip-lever *G*.

In practical use, the frame being secured to the pedal, the levers *H* *I* are set "straight," 5 in which position the point *N* engages the notch *O*, forcing the trip-lever *G* against the pressure of the spring *M* at such an angle as will prevent contact between the trip-arm *F* and the trip-lever *G*, and this is the normal 10 position. When it is desired to give an alarm, by means of the foot the lever *H* is pressed toward the crank, forcing the point *N* out of the notch *O* and allowing the trip-lever to swing out to a right angle, so as to form a 15 contact with the arm *F* as it is carried past. Thus each arm used causes a stroke of the clapper each time it passes the trip-lever. It is obvious that the same results may be reached by slight modifications, such as re- 20 versing the relative positions of the controlling-levers by pivoting the trip-lever and the clapper-arm at the same point and various other unimportant changes, and I therefore do not confine myself to the particular form 25 of details shown.

Having thus described my invention, what I claim, and desire to secure by Letters Patent, is—

1. A bicycle-bell comprising in combination 30 a frame secured to the lower side of a bicycle-pedal, a bell or gong secured to the frame, a clapper mounted in the frame at the under side thereof, a spring to press said clapper toward the inner edge of the bell, a trip- 35 lever pivoted approximately near its center and having one end engaging the arm of said clapper and an opposite end extending outward from said frame, a notch in one side of said trip-lever, a controlling-lever pivoted

on said frame and having one end adapted to 40 engage said notch and an opposite end adapted to be pressed by a rider's foot, and a trip-arm secured to the crank of the bicycle and adapted to form a tripping contact with said trip-lever, substantially as shown and de- 45 scribed.

2. In a bicycle-bell, the combination of the supporting-frame secured to the pedal-frame, the bell or gong supported by the said supporting-frame, the clapper having the end of 50 its arm pivoted to said supporting-frame and spring-pressed, the trip-lever pivoted to said supporting-frame and having its inner end in engagement with said arm, the notch in the side of said trip-lever, the controlling-lever 55 pivoted to said supporting-frame and adapted to engage said notch to place said trip-lever in or out of operative position, and the trip-arm secured to the crank or pedal-axle and adapted to engage said trip-lever when in 60 operative position, substantially as shown and described.

3. In a bicycle-bell, the combination with the bell-clapper arm suitably mounted, of the trip-lever pivoted adjacent to and connected 65 at one end with said clapper-arm and provided with the notch in the side thereof, the controlling-lever suitably mounted and adapted to engage said notch, and the trip-arm secured to the crank or pedal-axle to operate 70 said trip-lever, substantially as shown and described.

In testimony whereof I affix my signature in presence of two witnesses.

HORACE Q. PLUMMER.
